UNITED STATES PATENT OFFICE

2,439,988

BOLLARD

Donald A. G. Ross, West Vancouver, British Columbia, Canada

Application July 3, 1944, Serial No. 543,250

1 Claim. (Cl. 254—176)

1

My invention relates to improvements in bollards.

When a ship is being warped into position or being moved from one berth at the pier to another, the hawser is sent ashore in the usual way and the bight led through fairleads to the most convenient winch drum and hauled taut. It is then invariably taken off the winch drum and made fast to the nearest bollards. During this process the line has slackened to a greater or less degree depending on the speed of transfer from winch drum to bollard, and also the intensity of tide or wind affecting the ship.

It is therefore, among the objects of the present invention to provide means whereby the removal of a hawser or line from a winch to a bollard becomes unnecessary, and to provide a means for both tightening and holding a line which can be conveniently placed at the side of a ship where the seaman can see the entire length of the outboard portion of the line that he is controlling. A further object is to dispose the component parts of the bollard and its controlling means, that it can be effectively operated by a seaman without it being necessary to change from one position to another.

The invention contemplates a bollard having two horns, one of which is rotatably mounted, as will be more fully described in the following specification and shown in the accompanying drawings, in which—

Fig. 1 is a longitudinal sectional view.

Fig. 2 is a sectional view taken on the line 2—2 of Figure 1.

Fig. 3 is a perspective view showing the bollard and the normal disposition of a line thereon.

In the drawings like characters of reference indicate corresponding parts in each figure.

The numeral 1 indicates generally a portion of a ship's deck which is supported upon deck beams 2. Supported from a wood base 3 is a bollard 4 which consists of a base 5 having an integral vertical horn 6 projecting upwardly therefrom adjacent one end and a bearing 8 is provided adjacent the opposite end of said base. A vertical shaft 9 having a suitable anti-friction thrust bearing 10 is mounted within the bearing 8 and is fitted at its lower end with a worm gear 12. A winding drum 14 is secured to the upper end of the shaft 9 and is driven from the worm wheel 12 by means of a worm 15, a pair of bevel gears 16 and a vertical shaft 17 from any suitable source of power, not shown. The winding drum is of substantially similar diameter to that of the horn 6.

The power source is controlled by means of a

2

control wheel 19 housed within a recess 20 in the upper face of the horn 6 and fitted to a shaft 21 which extends downwardly therethrough. The drum 14 and the horn 6 are so spaced as to provide easy manipulation of a line about both.

In use in warping a ship into position, the winding drum 14 is set in motion and a line passed around it and held taut to provide the necessary hauling grip, when the desired amount of line has been hauled in, a bight is taken also around the horn 6, the drum is then stopped by manipulating the control wheel 19. When the drum comes to rest, the line may be passed around the drum and horn in the form of a figure eight to prevent endwise movement as shown in Figure 3.

If the line is to be eased off, it is taken off the horn and the drum and then passed around both in the same manner as when using the conventional bollard, and is paid out as desired.

Obviously the circumstances will indicate to the seaman the proper manipulation of the line, but in every case it will be possible for him to bring his ship to exactly the position he desires it to remain and to make fast without having any slack in the line, if he so desires.

What I claim as my invention is:

A bollard comprising a base, a pair of upstanding members spaced apart, one of said members being substantially cylindrical in form about a vertical axis and being non-rotatable, the second of said members being substantially in the form of a truncated cone and mounted on a vertical shaft parallel to the vertical axis of the first named member, means adapted for connection to a source of power for rotating the second named member, and means for controlling the rotation of said member, said means being located within the upper end of the non-rotatable member.

DONALD A. G. ROSS.
